ALEXANDER G. WHITEHEAD, OF HARTFORD, AND EUGENE J. SULLIVAN, OF EAST HARTFORD, CONNECTICUT, ASSIGNEES TO PRATT & WHITNEY COMPANY, OF NEW YORK, N. Y., A CORPORATION OF NEW JERSEY.

FOLLOW REST FOR LATHES.

Application filed May 8, 1924. Serial No. 711,823.

This invention relates to a follow rest for lathes and in particular to a work supporting rest adapted to be mounted on and moved with the tool support and adapted to bear against the work at a point opposite the point of engagement of the tool.

A principal object of the present invention is to provide a follow rest for lathes that may be mounted directly upon and be longitudinally adjustable relative to the tool rest.

Another object of the invention is to provide a simple, inexpensive form of follow rest adapted to be readily adjustable for different positions of the tool and having a pair of rollers in engagement with the work at spaced apart points, one of which rollers is positioned directly opposite the point of contact of the tool.

Another object of the invention is to provide a follow rest adapted to engage a dove-tail way provided on a supporting member fastened to the upper surface of the tool rest so that it may be moved with and in a direction parallel to the movement of the tool, and also to provide a member transversely adjustable in said member for adjusting the roller of the follow rest for different diameters of work.

A still further object of the invention is to provide a pivotal mounting on the follow rest for one of the work engaging members or rollers so that it may be adjusted on the transversely adjustable member for different diameters of work, thus forming a supplementary support for the work.

With these and other objects in view, our invention consists in the features of construction and operation set forth in the following specification and illustrated in the accompanying drawing.

In the accompanying drawing annexed hereto and forming a part of this specification, we have shown our invention embodied in a work rest for a medium size lathe but it will be understood that the invention can be otherwise embodied and that the drawing is not to be construed as defining or limiting the scope of the invention, the claims appended to this specification being relied upon for that purpose.

In the drawing:

Figure 1 is a transverse sectional view of the complete follow rest taken on line 1—1 of Fig. 2.

Fig. 2 is a plan view of the complete follow rest, and

Fig. 3 is a sectional view taken substantially on line 3—3 of Fig. 1.

In the above mentioned drawing, we have shown but one embodiment of the invention which is now deemed preferable but it is to be understood that changes and modifications may be made within the scope of the appended claims without departing from the spirit of the invention.

Briefly, and in its broadest aspect, our invention comprises the following principal parts: first, dove-tail ways forming a part of the tool support and extending in a direction parallel to the movement of the tool during its operation; second, a body member adapted to be mounted on and adjustably secured to said ways in any longitudinal position; third, a bar extending transversely through the body member and having a work engaging roller depending from one end; fourth, adjusting means for the bar; fifth, a supplemental roller mounted on a freely swinging arm in the bar; and sixth, means to retain the supplementary roller securely in any adjusted position.

Referring more in detail to the figures of the drawing, we show a portion of a tool cross-slide 10 of an engine lathe on which may be mounted a tool holder 11 of special form. This tool holder 11, as shown, is provided with a central bolt 12 by means of which it may be rigidly secured to the tool cross-slide 10. One or more tools 13 may be provided and adjustably secured in the holder 11 in the manner clearly shown in the figures. The tool holder is provided with two short vertical projections 14 at opposite sides, the space between them being ample for placing the cutting tools 13 of any desired form. Two of such tools 13 are shown, the space between them being filled with suitable spacers.

Just above the tools 13 is provided a dove-tailed member 15 preferably secured to the tool holder 11 by screws 16 extending into

the projections 14. This member 15 extends in a direction parallel to the direction of movement of the tool 13 during the cutting operation. The tools 13 are secured in position in their holder 11 by screws 17 through this member 15, two of which are shown for each tool. Also a screw 18 may be provided passing through one of the projections 14 to hold the tools 13 from lateral displacement. Adjusting screws 19 in rear of the tools 13 for forcing them forward and for holding them rigidly in adjusted position may also be provided if desired.

Mounted on this member 15 and engaging dove-tailed ways thereon is a body member 20 provided with a clamping screw 21 so that it may be securely clamped in any desired and adjustable position along the member 15. Extending transversely through the body member 20 is a bar 22 having a depending head portion 23 at its inner end. By means of a screw 24 entering one end of this bar 22 and engaging a nut 25 at the forward end of the screw 24, the position of the bar 22 may be adjusted transversely. To prevent rotative movement of the bar 22, which may be of circular section, a screw 26 is mounted in the body member 20 and contacts with the bar 22 on a flattened portion.

Mounted in the head portion 23 of the bar 22 and at its lower end is a small, freely rotatable work engaging roller 27. It will be seen from this construction that the bar 22 may be adjusted transversely relative to the tool 13 so that the small roller 27 may engage a portion of the work W being turned. Also this roller 27 may be adjusted for any diameter of work W or position relative to that of the tool 13.

Also mounted on the head portion 23 of the bar 22 is a freely swinging arm 28 pivoted as shown in Fig. 2 and having a small roller 29 at its lower or free end. This roller 29 is adapted to engage a portion of the work W being turned spaced from the point of engagement of the first roller 27. The positions of this arm 28 and roller 29 are clearly shown in Fig. 2 for work of relatively large diameter. By means of an adjusting screw 30, the position of this roller 29 may be varied and it may be forced to any adjusted position against the work W. To hold this supplementary roller 29 in adjusted position, clamping screws 31 and 32 are provided. One of these screws 31 bears against

the pivot carrying the arm 28 and the other screw 32 forces a bearing member against the adjusting screw 30.

What we claim is:

1. A follow rest for lathes comprising in combination, a tool support, a supporting member thereon, a body member adapted to be mounted on the supporting member and movable with the tool support of the lathe, means on said supporting member to adjust the position of the member longitudinally of the tool support, a bar movable transversely in said member upon a fixed axis, a work engaging roller rotatably mounted in fixed position on the inner end of said bar, and means to hold said bar with the roller in any adjusted position. 60

2. A follow rest for lathes comprising in combination, a tool support, a supporting member thereon, a body member adapted to be mounted on the supporting member and movable above the tool support of the lathe, means above said tool support to adjust said body member in the direction of movement of said tool support, a bar movably mounted in said member, a work engaging roller depending from said bar, and means to hold said bar with the roller in any adjusted position. 75

3. A follow rest for lathes comprising in combination, a body member adapted to be mounted on and movable with the tool support of the lathe, a bar movably mounted in said member, a work engaging roller on said bar, a supplementary roller pivotally mounted on said bar, means to hold said bar with the first roller in any adjusted position, and means to hold the supplementary roller in any adjusted position relative to said first roller. 85

4. A follow rest for lathes comprising in combination, a body member adapted to be mounted on and movable with the tool support of the lathe, a bar movably mounted in said member, a work engaging roller on said bar, a pivotally mounted arm adjustable on said bar, means to hold said bar with the first roller in any adjusted position, and means to secure the pivotal arm in any desired position. 100

In testimony whereof, we hereto affix our signatures.

ALEXANDER G. WHITEHEAD.
EUGENE J. SULLIVAN.
